ANTI-MOUTH INHALER

Filed Oct. 17, 1922

Inventor

inventor
Solomon C. Pool

UNITED STATES PATENT OFFICE.

SOLOMON C. POOL, OF NEW YORK, N. Y.

ANTI-MOUTH INHALER.

Application filed October 17, 1922. Serial No. 595,178.

To all whom it may concern:

Be it known that I, SOLOMON C. POOL, a citizen of the United States, residing at 315 West 57th Street, New York city, in the 5 county of New York and State of New York, have invented a new and useful Anti-Mouth Inhaler, of which the following is a specification.

The invention relates to a device for the 10 prevention of mouth inhalation at all times when worn (while conversing, exercising, and so forth), the object being to instruct in, and accustom the user to, the nasal method of inhalation, which method I believe is, 15 and is generally regarded as, the better and more sanitary manner of breathing.

One form of the invention is illustrated in the accompanying drawing in which Fig- 20 ure 1 is a perspective view; Fig. 2 rear face view; Fig. 3 is a section on line 3-3 of Fig. 2; and Fig. 4 is a section on line 4-4 of Fig. 2.

13 is a movable piece in entirety; 16 16 are guides; and 17 17 elastic bands or cords. 25 13 is connected, by means of guides, with the fixed or largest part (hereinafter always called the major piece). (13 hereinafter is sometimes called the minor piece). Said major and minor pieces in conjunction with the 30 valve 11, which all fit closely together at all points of contact, completely cover or encase the mouth. Said valve is for preventing the intake of air and permitting the outlet of breath through the mouth. 15 15^a 15^a are 35 members of 13 and co-operate with said 13. 18 18^a 18^a and 19 are attachment pieces for holding the device in place.

The said major piece contains a member 10^d which extends and fits, on a curved edge 40 or surface, over the upper portion of the mouth (between the nose and upper lip) and 10^e 10^c extend along the sides of the mouth (between the cheeks and mouth); 13 contains a member 14 with curved edge or 45 surface extending along and under the lower portion of the mouth (between the lower lip and chin, following along the natural indentation found thereat); and said major piece contains a casing 10. The aforesaid 50 major and minor pieces are attached by means of guides 16 16 and also joined by elastic bands 17 17 to prevent them easily becoming separated, said 17 17 being fur- 55 ther referred to hereinafter. 11 is a valve of thin light material with a hinge at 12. 18 is a non-elastic cord for going over the

top of the head and is attached at 10^a 10^a. 18^a 18^a are extensions of 18 with stop pieces at 10^a 10^a, or with knots or pieces attached on the cord, for purpose of holding the device in position required. 19 is attached to 18^a at 18^c and attachable at 18^b by means of a hook and loop or eye, said 19 being elastic. 19 is to extend around the neck and may be made of various lengths or adjustable at 19^b. 60 The above-said cords are detachable from the device at 10^a 10^a, for purpose of replacement or for any other purpose. Said cord 18 is non-elastic for the reason that it is to hold the device steadily in position 70 (which is practicable, as the upper inner portion of the mouth always remains stationary with respect to the lower, and the upper lip consequently rarely, if ever, descends below the normal position while talking and in any other uses of the mouth for breath exhalations). 19 is elastic for the purpose of enabling the wearer to turn the head to the right or left or upward or downward without the otherwise rigid tension of 80 a non-elastic cord preventing or hindering the movement. 75

18 and 18^a 18^a may consist of a small chain instead of cord, and said 18^a 18^a may also consist of two cords instead of one, each 85 attaching at different points, in the same line as 18^a, lengthwise on the sides of the major piece (Fig. 1), a sufficient distance apart to hold the device somewhat more securely in place; however, this rearrange- 90 ment is not especially necessary.

15 and 15^a 15^a are members of 13 and encircle the chin, and 15 fits underneath the chin. Said 15 may be made of pliable or flexible material and consequently bent or 95 forced upward or downward so as to conform properly with the contour of the lower part of the face of the wearer. 15 and 15^a 15^a may be made of the same material as other main parts of the device or of wire 100 or other suitable material; or may be made as a separate part, and attachable at its juncture with the remaining part of 13. Said 15 15^a 15^a will serve also to make the whole of 13 balance and work together more 105 straightly and smoothly along the aforesaid guides 16 16.

The elastic bands 17 17, previously referred to, are detachable and when attached will assist, by tension, to bring 13 upward 110 to its proper place, if said 17 17 are short enough for that purpose, or the said bands

may be longer so as neither to assist nor interfere at all with the movement of 13. Said 17 17 will also permit, partly or entirely, of the separation of 13 from the major piece, for the purpose of cleansing, oiling, repairing, replacing or any other purpose desired.

20 is cut away, so as to make a curved piece, except near where it joins the major 10 piece and where it forms part of the casing in connection with 10 (Fig. 1). Said 20 also serves for points of attachment for 17 17, as well as incidentally the additional purpose of bracing the major piece to strengthen 15 the device.

11^a is a member of 20 and forms, in conjunction with the upper edges of 10^d, the seat of the valve 11.

10^a 10^c may be of greater or less thickness, 20 according to the material used and the comfort of the wearer required, and the edges more or less inclined to the sides. The major piece may be longer or shorter, or the whole device larger or smaller, as necessary for various conformations of faces.

The device, in main, may be constructed of aluminum, duralumin, gun-metal or other metal or any suitable substance.

10^a and 14 may be cut, formed, moulded, 30 altered or otherwise made so as to have either more or less curvatures than shown in the drawing, in order properly to fit the wearer.

The device is capable of receiving a variety of ornamentations.

35 The under side of the valve, where it comes in contact with the seat, may have a lining of cloth or other suitable material, for the purpose of preventing any excessive noise on closing of the valve.

40 Obviously many variations in shape and arrangement of parts could be made without departing from the spirit of my invention, and my drawings will be taken as in a sense diagrammatic.

45 The use and operation of my invention are as follows: After making the necessary adjustment of cords, the main part of the device is preferably, first, placed over the mouth and the non-elastic cord is carried

50 over the crown of the head; and, next, the elastic cord is brought around the neck and attached to a projection on the side of the device or, by means of hook and eye or loop, to an extension of the non-elastic cord.

55 When thus placed in position the device will operate, whenever the mouth is opened and closed, by the minor piece moving along, or telescoping, within the major piece, the two pieces being held together by means of lead-

60 ers or guides. The minor piece contains a transverse plate attached to the sides of the said minor piece with a curved edge running along and fitting into the indentation between the lower lip and chin and which 65 transverse plate will contribute, by pressure,

to the moving of the minor piece downward and upward within the major piece upon the opening and closing of the mouth. This movement may be assisted by the elastic bands attached to the major and minor pieces 70 which elastic bands will be caused (by means of the aforesaid transverse plate and the part underneath the chin) to extend with the opening of the mouth and which bands will contract with the closing of the mouth, this 75 contraction thus helping to bring the minor piece back to its former position; and the parts of the minor piece extending around and underneath the chin will serve the purpose of causing the minor piece to operate 80 more truly along its guides.

The valve which is attached by a hinge to the uppermost outer portion of the major piece, and which valve is normally seated upon the borders of the opening in the upper 85 portion of the major piece, will be raised from its seat, or opened, by and for the outlet of breath and will be reseated, or closed, upon any attempted intake of air into the mouth. The combination consisting of the 90 major and minor pieces and the valve completely covers or encases the outside of the mouth.

This combination will permit the wearer to open and close the mouth for speaking or 95 any other necessary purpose while preventing the intake of air through the mouth, thus compelling the wearer to use the nostrils for inhalation at all times when worn, the purpose being to train and accustom the wearer 100 to the habit of nose inhalation so as eventually to make use of this habit at all ordinary times.

Even should the device not fit the wearer perfectly and thus, or otherwise, not entirely prevent the intake of air through the mouth, it would nevertheless serve for training and instructional purposes by the cutting off of so large an intake of air through the mouth and the sound caused by the sharp 110 closing of the valve would give notice of any attempted mouth inhalation which is sought to be prevented.

I claim:

1. In an anti-mouth inhaler, a major piece 115 constituting a casing extending along the sides and over the mouth of the wearer with an opening in the upper part thereof for the outlet of breath and provided with guides, and a minor piece adapted to move along 120 said guides within the major piece and having a transverse plate with a curved edge to fit into the indentation between the lower lip and chin.

2. In an anti-mouth inhaler, a major piece 125 constituting a casing extending along the sides and over the mouth of the wearer with an opening in the upper part thereof, a valve closing said opening and adapted to open for the outlet of breath, and said major piece 130

provided with guides, and a minor piece adapted to move along said guides within the major piece and having a transverse plate with a curved edge to fit into the indentation 5 between the lower lip and chin.

3. In an anti-mouth inhaler, a major piece, a movable minor piece with a transverse plate secured to the upper part thereof; and elastic bands secured to said transverse plate 10 and to the major piece for attaching the major and minor pieces together, and for assisting in the operation of the minor piece within the major piece.

4. In an anti-mouth inhaler, a major piece, 15 a movable minor piece with a transverse

plate secured to the upper part thereof, and a part of said minor piece adapted to extend around and under the chin, and elastic bands secured to the transverse plate of the minor piece and to the major piece. 20

5. In an anti-mouth inhaler, a major piece with projections on each of the sides thereof, a non-elastic cord attached to said projections and adapted to extend around the head of the wearer and an elastic cord secured to 25 an end of said non-elastic cord and adapted to extend around the neck and removably attached to the other end of said non-elastic cord for holding said major piece in place.

SOLOMON C. POOL.
